UNITED STATES PATENT OFFICE

159,155

ATHLETIC SHIRT

Joseph W. Kelly, Norwood, and Ansel Wilfred Fairbanks, Cheviot, Ohio, assignors to Sport Products, Inc., Cincinnati, Ohio, a corporation of Ohio

Application August 31, 1948, Serial No. 148,376

Term of patent 14 years

(Cl. D3—25)

To all whom it may concern:

Be it known, that we, Joseph W. Kelly and Ansel Wilfred Fairbanks, citizens of the United States, residing at Norwood, Ohio, and Cheviot, Ohio, respectively in the county of Hamilton and State of Ohio, have invented a certain new, original and ornamental Design for an Athletic Shirt, of which the following is a full, clear and exact description, reference being had to the accompanying drawings, forming a part hereof.

Description of figures:

We claim:

The ornamental design for an athletic shirt, as shown.

JOSEPH W. KELLY.
ANSEL WILFRED FAIRBANKS.
